A. H. HOOKER.

ELECTROLYSIS OF SOLUTIONS AND APPARATUS THEREFOR.

APPLICATION FILED AUG. 5, 1920.

1,388,466.

Patented Aug. 23, 1921.

UNITED STATES PATENT OFFICE.

ALBERT H. HOOKER, OF NIAGARA FALLS, NEW YORK, ASSIGNOR TO HOOKER ELECTRO-CHEMICAL COMPANY, OF NEW YORK, N. Y., A CORPORATION OF NEW YORK.

ELECTROLYSIS OF SOLUTIONS AND APPARATUS THEREFOR.

1,388,466.

Specification of Letters Patent. Patented Aug. 23, 1921.

Application filed August 5, 1920. Serial No. 401,391.

To all whom it may concern:

Be it known that I, ALBERT H. HOOKER, a citizen of the United States, residing at Niagara Falls, in the county of Niagara 5 and State of New York, have invented certain new and useful Improvements in Electrolysis of Solutions and Apparatus Therefor, of which the following is a specification.

10 This invention relates to the electrolytic decomposition of solutions, and more particularly to the electrolytic decomposition of sodium chlorid solutions in a cell of the diaphragm type, the primary objects of the 15 invention being to provide an improved apparatus and process for the foregoing purposes.

According to the invention in its preferred embodiment the electrolytic cells 20 receive in unit time a feed of a constant volume of electrolyte, for example an aqueous solution of sodium chlorid, said electrolyte carrying salt, (typically sodium chlorid) in excess of the amount normally soluble 25 therein at the operating temperature, this excess of salt being of course present in solid phase at the moment of introduction of the electrolyte into the cell.

In the practical operation of the process, 30 the quantity of salt thus supplied in solid phase is nearly but not quite sufficient to maintain the brine within the cell in a condition of complete saturation at the operating temperature: an excess of solid salt 35 above the quantity required for the saturation of the electrolyte within the cell should however be carefully avoided, as leading to the clogging of the diaphragm and otherwise interfering with the smooth con- 40 duct of the operation.

In explanation of the desirability of proceeding in the manner outlined above, it may be explained that it is a well established fact that if unsaturated brine is fed 45 to an electrolytic cell of the diaphragm type at the rate necessary merely to maintain percolation through the diaphragm, without an overflow, the gravity of the brine within the cell falls below that of the feed 50 brine by a definite amount, which is dependent upon the percentage of decomposition. For example in a special case, operating under conditions as above, the brine within the cell was found to contain on the 55 average 254 grams of salt per liter, although

the feed brine during the same period contained 285 grams per liter. The dilution within the cell was therefore approximately to 89% of the original concentration. The explanation of this phenomenon appears to 60 be that a certain proportion of the water is left behind upon the anode side of the dia- phragm. The lower gravity thereby result- ing lessens the viscosity of the solution and increases the percolation through the dia- phragm, so that the operation of the cell 65 soon becomes stabilized: but the specific gravity of the solution within the cell is permanently lowered. This is objectionable as tending not only to a higher operating 70 voltage but to a lower concentration of caus- tic solutions.

My researches have indicated that the above described dilution of the brine is a function of the quantity of caustic pro- 75 duced; and that for every 100 grams of caustic delivered from the cell approxi- mately 180 grams of water are left behind in the cell. If, for example, the feed brine contains 292.5 grams of sodium chlorid per 80 liter and the per cent. of decomposition is 50, this will amount to about 21% of the total water delivered to the cell with the in- flowing brine. If it were possible to dis- 85 charge this water from the anode side of the cell, the amount of water to be evaporated from the caustic would of course be corre- spondingly reduced: but the same object may be attained by keeping the concentra- 90 tion of the liquor within the cell approxi- mately up to that of the feed liquor; or in other words as near as practicable at the saturation point.

An obvious method of maintaining the 95 concentration of the brine within the cell is to add solid salt to the cell, and it has frequently been proposed to maintain within the cell a supply of solid salt sufficient for this purpose. According to my re- 100 searches however such salt must be added gradually or continuously and in strictly measured quantity; for if too large a quan- tity is added in unit time, or if it be at- tempted to maintain a permanent supply of 105 solid salt within the cell, the diaphragm will rapidly become obstructed and the nor- mal operation of the cell will be seriously affected. Hence, as above stated it has proven impracticable to accomplish this re- 110 sult by maintaining a supply of solid salt

- at all times in contact with the electrolyte within the cell, as has often been proposed. My researches have shown that only such quantity of salt may be added as will, from a practical or operating viewpoint, pass immediately into solution; and the brine within the cell should at all times be kept safely below the saturation limit at the operating temperature.
- 10 For a full understanding of the invention reference is made to the accompanying drawings illustrating a typical system suitable for carrying the present process into effect, it being however understood that the invention is not restricted to the particular means chosen for illustration.

In said drawings:

Figure 1 is a diagrammatic elevation, partly in section, of a typical circulating 20 and feeding system; Fig. 1^a being a plan view of the constant level tank 6;

Fig. 2 is a partial vertical section of the same on a slightly enlarged scale on line 2-2 of Fig. 1; and

25 Figs. 3, 4 and 5 are detail sectional views of various types of feed nozzles which may be employed.

Referring to Figs. 1, 1^a and 2, 2 represents the brine storage tank; 3 the salt hopper containing fine granulated salt such as may be obtained by evaporation of the caustic liquor produced in the operation of the cells; 4 the mixing and agitating tank; 5, 5, 5, the electrolytic cells; and 6 the level-regulating tank.

The tank 4 is filled with brine from the tank 2 by opening the valve 7. 8 is a brine-metering device which may be power-driven or may take the form of a geared rotor 40 pump of the Root blower type, as more clearly illustrated in Fig. 2. The brine flowing through this metering device turns the rotor 9, which drives the sprocket 10, and, through chain 11, the large sprocket 45 12, the latter revolving a double-flight worm conveyor 13 which extends throughout the length of the salt hopper at the bottom thereof. This worm feeds the dry salt forward into the vertical open-ended pipe 14. 50 The stream of brine from tank 2 is likewise directed into the pipe 14, where it washes the salt out of the worm as fast as it is fed forward, and carries it through the screen 15 and chute 16 into the mixing and agitating tank 4. There is therefore in the operation of this device, a fixed relation between the displacement of the brine-meter and the salt feed; so that a definite and controllable quantity of salt can be fed for a given 80 quantity of brine. The feed ratios may be adjusted as desired by a proper choice of sprockets 10 and 12.

It will be understood that the tank 2 might be filled with water or weak brine, 65 and by feeding the proper quantity of solid

salt a saturated, under-saturated or over-saturated brine can be delivered into tank 4 at will. For the purpose of the present invention, however, a brine carrying an excess of salt in solid phase will be required; and it is generally preferable to obtain this by filling the tank 2 with brine having a specific gravity in the neighborhood of 1.2, and adding through the hopper 3 the salt necessary to provide the required excess. 75

In the system chosen for illustration the tank 4 is provided with a centrifugal pump 17 driven by a motor 18. The intake 19 of the pump 17 is located close to the bottom of the tank 4, and agitators 20 are mounted 80 upon the vertical pump shaft. The delivery pipe 21 from pump 17 is carried over the cells 5 and terminates in an elbow 22, located within the level-regulating tank 6 and directed tangentially near the bottom thereof (see Fig. 1^a). 23 is the overflow inlet leading to the return pipe 24, terminating in an elbow 25 which may be directed tangentially near the bottom of tank 4. 85

By means of the pump 17 and the pipes 90 21 and 24 a rapid circulation of the salt suspension is maintained. Thereby the mixture in the tank 4 is kept in violent agitation and the undissolved salt is maintained in suspension during its flow to the tank 6 95 and return. 26 indicates a screen which may be placed across the tank 6 between the inflow and outflow to trap any foreign matter which may find its way into the system. A 20-mesh screen has proven satisfactory 100 for this purpose, being sufficiently coarse to permit free passage of the fine solid salt, while sufficiently fine to remove any foreign matter that would be liable to interfere with the feed of the brine to the cells or with 105 the operation of the latter.

Above each cell 5 is provided a feeding orifice or nozzle 27. A simple form of such orifice is illustrated on an enlarged scale in Fig. 3, comprising a calibrated glass tube 110 28 let into the pipe 21 through a rubber stopper by means of a tee 29. The stream of brine from the tube 28 is directed into a glass tee 30, which discharges in turn into the cells, for example through lengths of 115 rubber hose 31, connected with earthenware well-pipes 32, which extend to a point well below the liquid level. Naturally any preferred device may be used for conveying the salt suspension to the cells or distributing 120 it therein.

The hydrostatic head upon the orifice 27 is determined by the level of the liquid in the tank 6. This may be adjusted as desired by changing the effective height of the overflow pipe 23, which can conveniently be done by screwing different lengths into the coupling 33. So long as the level in the tank 6 is maintained constant, the orifice 28 will feed a constant quantity of brine in unit 125 130

time, this brine carrying therewith any desired excess of suspended salt. This rate of feed is unaffected by the level of the liquid within the cell 5 or by the gas pressure 5 therein.

Fig. 4 illustrates a stream-line type of orifice, screwed flush into the pipe 21 and terminating in a succession of tapered nozzles 34, screwed one upon the other, each 10 successive nozzle being slightly smaller than the preceding one with the result that together they form a uniformly tapering orifice of which the aperture may be closely regulated.

15 The types of orifice illustrated in Figs. 3 and 4 are not affected by the velocity of the flow in pipe 21, except as the resistance to such flow creates added static pressure. Thus, if the pipe 21 be horizontal, the orifice leading to the cell farthest from the tank 6 will be under a higher static pressure than that of the cell nearest this tank, by the amount of the pressure necessary to overcome the resistance offered by the walls of 20 the pipe 21 to the flow of the salt suspension therein. In order to equalize the static head on the several orifices, and thereby to equalize the flow through these orifices, the pipe 21 is preferably inclined toward the 25 regulating tank 6 as illustrated in Fig. 1. It is very easy to determine experimentally the degree of inclination necessary by connecting a manometer to each orifice, the proper inclination being obtained when all of the 30 manometers give identical readings.

35 Fig. 5 illustrates a form of orifice having a curved inlet 35 extending into the interior of the pipe 21. This type of orifice may be adjusted by turning it so as to present various angles to the direction of flow within the pipe, and is very sensitive to fluctuations in the velocity of the brine.

It is to be noted that by operating in accordance with the present invention I am 40 able not only to feed to the several electro- 45

lytic cells a brine carrying solid salt in suspension, but to feed a constant quantity of this suspension in unit time. By applying this method to a diaphragm cell having no overflow or equivalent constant-level device, 50 I secure an accurate and wholly automatic control of the percolation through the diaphragm, since the level of electrolyte within the cell will automatically vary in the direction and to the precise degree necessary 55 to secure an average percolation equivalent to the inflow. Thereby I am able to insure a constant percentage of decomposition and a constant and high ampere efficiency; while the maintenance of the saturation of the 60 electrolyte leads to a relatively high emergency efficiency. This result in the particular system chosen for illustration is dependent upon the maintenance of a constant level in the pressure-regulating tank 6; but 65 it will be obvious to those skilled in this art that other means may be employed for accomplishing the same result.

The circulating system described herein as a preferred means of securing uniform feed 70 to the electrolytic cells is claimed in a co-pending application Serial Number 403,826 filed Aug. 13, 1920, by Thomas L. B. Lyster and Kenneth E. Stuart.

I claim:—

1. In a process of electrolyzing salt solutions, the step which consists in supplying to the cell an aqueous electrolyte carrying a salt in solid phase.

2. Process according to claim 1 in which the quantity of salt introduced in unit time is proportioned to maintain approximate saturation of the electrolyte within the cell.

3. The combination with an electrolytic cell, of means for supplying thereto in unit time a fixed volume of electrolyte carrying salt in solid phase.

In testimony whereof, I affix my signature.

ALBERT H. HOOKER.
